PUMP

Clifford J. Griffith, Dimondale, and James P. Carr, Lansing, Mich., assignors to Food Machinery and Chemical Corporation, San Jose, Calif., a corporation of Delaware

Application October 13, 1954, Serial No. 462,002

3 Claims. (Cl. 309—33)

This invention relates to improvements in pumps and more particularly to improved means for controlling the flow of fluid through a reciprocating pump.

In pumps used for circulating certain types of chemical solutions, such as insecticides, it is very important that none of the liquid be permitted to directly contact the moving parts of the pump or be permitted to reach the oil in the crankcase, since many such chemical solutions will attack the connecting rod bearings and crankshaft bearings of the pump causing considerable damage.

It is, accordingly, an object of the present invention to provide a pump having novel means for preventing the liquid being pumped from gaining access to the moving parts of the pump mechanism.

Another object is to provide an improved and simplified valve arrangement for a reciprocating pump.

Another object of the present invention is to provide a novel piston for a reciprocating pump.

Another object is to provide a reciprocating pump that is simple in construction and efficient in operation.

Other and further objects and advantages of the present invention will become apparent from the following description taken in connection with the accompanying drawings, in which:

Figure 1 is a perspective view of a pump constructed in accordance with the teaching of the present invention.

Figure 2 is a central vertical sectional view taken on line 2—2 of Fig. 1.

Figure 3 is an enlarged elevation taken along line 3—3 of Fig. 1, inlet and discharge conduits for the valve structure being shown.

Figure 4 is an enlarged sectional view taken on line 4—4 of Fig. 3.

Figure 5 is an enlarged fragmentary sectional view taken along line 5—5 of Fig. 4.

In Figs. 1 and 2 the reference numeral 10 indicates generally a hollow pump housing having opposed side walls 12 and opposed end walls 13. All four walls of the housing are integrally formed and have upper, inwardly slanted portions 14 connected at their top ends by an integrally formed top wall 15 which has two vertical bores 16 (Figure 2) formed therein. A cross head 20 is mounted in each bore for vertical reciprocation therein by means of a wrist pin 21, a connecting rod 22 and a crankshaft 23. The crankshaft is journaled for rotation in bearing assemblies 24 in spaced apertures 25 formed in the lower ends of the housing walls 12.

Each crosshead has an upwardly extending rod 30 slidably journaled in a guide sleeve 31 which is rigidly secured in the upper end of the bore 16. A piston assembly 35 is mounted on the upper end of each crosshead rod and is arranged for sliding movement in a cylinder 36 provided by the internal surface of a sleeve 37. Each sleeve is disposed at its upper end in a recess 40 in a pumping head 41 and, at its lower end, in a recess 43 in a mounting plate 44 which is supported on and secured to the upper surface of a wall 45 which is integrally

2

formed on the housing and extends around the upper portion of the pump housing in spaced relation therewith.

It will be seen that, when the crankshaft is rotated by a power mechanism (not shown), the piston assemblies 35 will be reciprocated in the cylinders. It is to be noted that the pistons are 180° out of phase so that, while one piston is on the suction stroke, the other piston is in the discharge stroke.

The pumping head 41 is secured on the upper end of the pump housing by bolts 48 (Figs. 2 and 4) that extend through suitable openings in the pumping head and are threaded into tapped openings in the mounting plate 44. The pumping head 41 has two flow passages 50 and 50a (Figs. 3 and 4) each of which extends between one of the pump cylinders 36 and a cylindrical chamber 52. Each cylindrical chamber 52 is in flow communication with an inlet chamber 60 through a port 61 and with a discharge chamber 63 through a port 64. Both of the inlet chambers 60 (Fig. 3) are in communication with a common inlet conduit 66 through an internally threaded passage 67 which receives one end of the conduit. Similarly, both discharge chambers 63 communicate with a common discharge conduit 68 through an opening 69 in which the conduit 68 is threaded.

25 A feature of the present invention is the novel valve arrangement for controlling the flow of liquid from each inlet chamber 60 to the associated discharge chamber 63. Each valve assembly comprises an annular inlet valve seat 70 (Fig. 4) arranged to fit snugly in a recess 71 in the pumping head 41. The valve seat has an outer annular groove 73 in which a resilient O-ring 75 is disposed in sealing engagement between the walls of the groove 73 and the wall of the recess 71. Resting on top of the seat 70 is a cylindrical cage 78 which has a plurality of vertical slots 79 through which fluid may pass. A solid valve disk 81 is positioned over the central opening of the annular valve seat 70 to close the passage formed therein. A coil spring 83 is seated at its lower end in a recess formed in the valve disk 81 and bears at its upper end against an annular discharge valve seat 85 which is snugly disposed in the port 64 formed in the pumping head. An O-ring 88 is disposed in an annular groove in the discharge valve seat 85 in sealing engagement between the outer surface of the valve seat 85 and the inner surface of the port 64. A solid valve disk 90 is positioned over the central opening of the annular valve seat 85 to close the passage formed therein. A coil spring 91 is seated at its lower end in a recess formed in the valve disk 90 and bears at its upper end against a cylindrical cover 92 which is disposed in a cylindrical passage 93 provided in the pumping head. A discharge cage 95 rests on top of the discharge valve seat 85 with its lower end extending into the port 64 in the pumping head 41. The cage 95 has a plurality of slots 96 through which liquid may pass. A resilient O-ring 97 is disposed in an annular groove in the cover 92 in sealing engagement between the cover and the pumping head. A bar 99 (Fig. 3) extends across the top of the pump housing and bears against both valve covers 92 to hold the valve assembly in place. The bar 99 is locked in position by a capscrew 100 which extends through the bar and is threaded received in the pumping head 41.

Referring to Fig. 4 it will be seen that when the piston 35 moves downwardly in its suction stroke, the inlet valve disk 81 is lifted off the seat 70 permitting liquid to enter the cage 78 and pass through the slots 79 of the cage 78 into the flow passage 50 and then into the cylinder 36. When the piston moves upwardly on a discharge stroke, the valve disk 81 is forced down onto its seat 70, while the discharge valve disk 90 is forced off its seat 85 permitting the liquid to be forced through the

slotted discharge cage 95 and out the discharge conduit 68.

Another feature in the present invention resides in the provision of means for effectively preventing the liquid being pumped from coming in contact with the moving parts of the pump. As seen in Fig. 5 each piston 35 comprises a cup-shaped yieldable packing ring 103 which fits snugly inside the pumping cylinder 36. The packing element is sealed on the cross head rod 30 by means of a sharp circular projection, or ridge, 104 formed integrally with a washer or pressure applying member 105. An O-ring 106 which is seated in a recess 107 in a back-up washer 108 seals the lower end of the packing element 103 to the rod 30. A capscrew 110 is threaded into a tapped opening in the upper end of the cross head rod and bears against the washer 105 to press the sharp circular projection 104 into the yieldable upper surface of the packing ring to form an effective seal and to expand the O-ring 106 into tight sealing engagement with the cross head rod 30, thus preventing the leakage of fluid downwardly along the surface of the rod.

When leakage occurs around the outer circumferential edge of the packing element 103 due to wear, the downwardly moving liquid is deflected outwardly by a shield or hood 115 (Fig. 2) which has an upper cylindrical portion 116 disposed around the reciprocating rod 30 and locked between the back-up washer 108 (Fig. 5) and a shoulder 118 formed on the rod 30. A lower enlarged cylindrical portion 119 (Fig. 2) of the shield 115 extends, even in the uppermost position of the piston, to a point below the upper end of the bore 16 in which the cross head 20 reciprocates. The result is that liquid leaking past the cup will run down over the hood and be directed to the outside of the casing. With this arrangement it is not possible for such liquid to contact the cross head rod 30.

From the foregoing description it will be evident that there is provided in the present invention a simple, effective valve arrangement for controlling the flow of liquid through a pump, and a positive gripping means for preventing leakage of liquid at the point of connection of the piston with the piston rod. Further, the novel piston rod hood provides an effective means for deflecting liquid away from the rod.

It will be understood that modifications and variations of the embodiment of the invention disclosed herein may be resorted to without departing from the scope of the novel concepts of the invention.

Having thus described our invention what we claim as new and desire to protect by Letters Patent is:

1. In a pump having a cylindrical pumping chamber, a piston comprising a rigid rod having a shoulder thereon, a rigid washer disposed around said rod above and adjacent to said shoulder, a packing ring of yieldable material disposed around said rod in abutting contact with said washer and having a cylindrical surface in sliding contact with the wall of the cylindrical pumping chamber, a compressible seal ring disposed between said rigid washer and said packing ring and having an inner surface disposed around said rod, an apertured pressure-applying member disposed around said rod adjacent

4
said packing ring, a ridge on said pressure member encircling said rod and in contact with said yieldable packing ring, and pressure-applying means for pressing said ridge into sealing engagement with said packing ring, 5 said packing ring being arranged to transmit the pressure of said pressure-applying means to said seal ring to compress said seal ring and move said inner portion into sealing engagement with said rod.

2. In a pump having a cylindrical pumping chamber, 10 a piston comprising a rigid rod having an outer peripheral shoulder, a rigid annular washer disposed around said rod above and adjacent to said shoulder, said washer having an annular recess in one face of the washer and adjacent said rod, a compressible seal ring disposed around said rod in said recess, a packing ring of yieldable material disposed around said rod in abutting contact with said washer and having a cylindrical surface in sliding contact with the wall of the cylindrical pumping chamber, and means for applying pressure to said packing ring to compress said seal ring and move it into sealing engagement with said rod and the walls of said recess.

3. In a pump for pumping liquids, means defining a cylindrical pumping chamber, a piston comprising a rod, 25 a rigid washer of substantially the diameter of said chamber disposed around said rod and having a flat supporting surface, a packing ring of yieldable material disposed around said rod above and in abutting contact with said flat supporting surface and having a cylindrical surface in sliding contact with the wall of the chamber, an apertured pressure-applying member disposed around said rod above and adjacent to said packing ring, a ridge on said pressure-applying member encircling said rod and in contact with said yieldable packing ring, means 30 for pressing said ridge into sealing engagement with said packing ring for preventing the passage of liquid inward toward said rod, and a shield disposed around said rod below and in abutting contact with said washer for deflecting liquid leaking past said piston away from said rod, said shield having a small diameter portion arranged to enter said cylindrical pumping chamber in spaced relation to the walls thereof and a large diameter portion disposed below the small diameter portion, said shield portions preventing access of the pumped liquid to the 35 moving parts of the pump.
